UNITED STATES PATENT OFFICE.

FRANK L. STEWART, OF GRAND RAPIDS, MICHIGAN, ASSIGNOR OF ONE-HALF TO WILLIAM T. LAMOREAUX AND ALLEN P. COLLAR, OF SAME PLACE.

DESIGN FOR A DUST-PAN.

SPECIFICATION forming part of Design No. 24,262, dated April 30, 1895.

Application filed December 10, 1894. Serial No. 531,423. Term of patent 7 years.

To all whom it may concern:

Be it known that I, FRANK L. STEWART, a citizen of the United States, residing at Grand Rapids, in the county of Kent and State of Michigan, have invented and produced a new and original Design for Dust-Pans, of which the following is a specification, reference being had to the accompanying drawings, forming part thereof.

10 Figure 1 is a side elevation, and Fig. 2 is a perspective, of my dust-pan, these two views being deemed necessary to fully illustrate my design.

15 The leading features of my design consist of a nose piece B inclined upward and backward to the line b', thence, a body A curved

downward and backward to a', see Fig. 1, thence upward and rolled to form a handle at C, a rim turned up and flaring outward from the body and nose piece and given an extra flare or scoop shape at D, and creases b indented into the body and nose piece.

Having thus pointed out the leading features of my design, what I claim is—

The design for a dust pan herein shown and described.

Signed at Grand Rapids, Michigan, December 6, 1894.

FRANK L. STEWART.

In presence of—

GEORGE H. WHITE,

ITHIEL J. CILLEY.
